UNITED STATES PATENT OFFICE.

CLARK SINCLAIR, OF HAWTHORNE, NEVADA, ASSIGNOR OF THREE-FOURTHS TO JOE A. BROWN AND WILLIAM O. PARKER, OF BRIDGEPORT, NEVADA.

SPRING-MOTOR.

SPECIFICATION forming part of Letters Patent No. 628,149, dated July 4, 1899.

Application filed June 21, 1898. Serial No. 684,092. (No model.)

To all whom it may concern:

Be it known that I, CLARK SINCLAIR, a citizen of the United States, residing at Hawthorne, in the county of Esmeralda and State 5 of Nevada, have invented certain new and useful Improvements in Spring-Motors, of which the following is a full and complete specification, such as will enable those skilled in the art to which it appertains to make and 10 use the same.

This invention relates to spring-motors; and it has for its object to provide a device of this character which may be connected with a baby-carriage to rock the same and 15 which is so constructed as to be readily moved about from place to place and which is capable of being stopped at will.

The invention consists of a spring-motor constructed substantially as hereinafter described, and defined in the annexed claim.

The invention is fully disclosed in the following specification, of which the accompanying drawings form a part, in which the separate parts of my improvement are designated 25 by the same letters of reference in each of the views, and in which—

Figure 1 is a view in perspective of my improved spring-motor, showing a connection with a baby-carriage for operating the same.

30 Fig. 2 is a side view of the spring-motor, the side of the casing being removed to show the construction. Fig. 3 is a top view thereof.

In the drawings, A represents my improved spring-motor, and E the connecting-cord, by 35 which the power is transmitted to a baby-carriage C, which is provided with the usual supporting-springs, as shown. The spring-motor A is inclosed in a suitable casing, in the sides of which is journaled the shaft b, upon which 40 is fixed the spring-operated drum B. The spring-motor A is mounted upon the rear axle of the baby-carriage C. This shaft b projects through the casing at one side and is squared on its outer end for the reception of a winding-key. The spring for operating the drum 45 is inclosed therein and is operatively connected in the usual manner to the shaft b and the drum B. At one end of the drum B is fixed a large gear-wheel b', which is in mesh 50 with a pinion d on the shaft d'. Near the op-

posite end of this shaft d' is fixed a gear-wheel D, and upon the outer end of said shaft outside the casing is fixed a disk D', provided with a pin eccentrically located upon its outer face, whereby connection may be had with the 55 cord E. Across the upper portion of the casing and near the end thereof opposite the spring-drum is arranged a transverse beam F, to which is secured one end of a spring f, at the outer end of which is attached a brake-bar f'. The brake-bar f' is so arranged as to bear against the face of the large gear-wheel b' and extends beyond the same out through a notched hole or aperture f² in one end of the casing. A lug or pin f³ is arranged 60 upon the side of the brake-bar which bears against the gear-wheel b' and is adapted to enter a perforation f⁴, formed in the face of the gear-wheel, whereby the rotation of the drum may be stopped.

The gear-wheel D meshes with a pinion G, fixed on a shaft g, located near the end of the casing, and upon the other end of the shaft g is arranged a worm g', adapted to mesh with a worm-wheel h, fixed upon a vertical shaft 75 H, journaled at its upper end in the cross-beam F and at its lower end in the casing. Near the upper end of the shaft H are fixed the blades of a fan h', which acts as a speed-governor for the spring-motor.

The cord E having been connected with the carriage and the spring in the drum wound up, the brake-bar is shifted so as to release the large gear-wheel and the mechanism begins to operate, jumping or rocking the carriage by the alternate tension upon and relaxation of the cord E in connection with the action of the carriage-springs, as will be readily understood. The end of the brake-bar is dropped into the notch of the aperture f², 90 whereby it is held out of contact with the gear-wheel b'. The mechanism may be instantly stopped by simply releasing the end of the brake-bar, whereupon the spring f forces the same against the gear-wheel b' and 95 the pin f³ enters the perforations f⁴.

Having fully described my invention, I claim as new and desire to secure by Letters Patent—

The combination with a carriage, the body 100

of which is provided with the usual supporting-springs, of a spring-motor mounted upon one of the axles of said carriage and provided with a rotating disk, and devices connecting said rotating disk and said carriage-body whereby said carriage-body is actuated, substantially as shown and described.

5 In testimony that I claim the foregoing as

my invention I have signed my name, in presence of the subscribing witnesses, this 11th 10 day of June, 1898.

CLARK SINCLAIR.
